J. N. LYLES

NONGLARE REFLECTOR

Filed Sept. 1, 1922

FIG. 1.

FIG. 3.

FIG. 2.

Inventor

James N. Lyles

Patented July 10, 1923.

1,461,362

UNITED STATES PATENT OFFICE.

JAMES N. LYLES, OF ADDISON HEIGHTS, VIRGINIA.

NONGLARE REFLECTOR

Application filed September 1, 1922. Serial No. 585,681.

To all whom it may concern:

Be it known that JAMES N. LYLES, a citizen of the United States, residing at Addison Heights, in the county of Arlington and State of Virginia, has invented certain new and useful Improvements in Nonglare Reflectors, of which the following is a specification, reference being had therein to the accompanying drawings.

- 10 This invention relates to nonglare reflectors, and has particular reference to reflectors of the character indicated adapted for use in connection with automobile headlights.
- 15 An important object of the invention is to provide such a reflector with means for eliminating the highly objectionable glare incident to the use of the ordinary parabolic reflectors.
- 20 An important object of the invention is the provision of a headlight reflector whereby all objectionable glare is eliminated, while at the same time all of the light from the lamp is utilized and directed upon those
- 25 portions of the road where it is most needed and desired.

A further object of the invention is the provision of a substantially parabolic reflector which can be made at approximately the same cost as the present reflectors, and will serve the purposes above set forth.

Other important advantages of the invention will be apparent during the course of the following description.

35 In the accompanying drawings, wherein like numerals are employed for designating like parts throughout,—

Fig. 1 is a vertical sectional view through a headlight, illustrating the invention in use;

40 Fig. 2 is a face view of the reflector removed from the headlight casing; and

Fig. 3 is a horizontal sectional view through the reflector, taken on line 3—3 of

45 Fig. 2.

Referring to the drawings, 5 designates the headlight casing, which may be of any well-known construction. The reflector is indicated by the numeral 6, and same may be stamped from a single piece of sheet metal, as is customary. The lower half of the reflector is formed substantially the same as the ordinary parabolic reflectors having the usual axis and focal point, and reflecting

55 surface 7. The rays of light from the bulb

8 strike the surface 7 and are projected in substantial parallel relation to each other, as clearly indicated in Fig. 1. The upper half of the reflector is formed of a series of stepped portions 9, 10, 11, 12, 13, 14 and 15, seven being shown, though the number may be increased or decreased as may be found advisable. Each of the steps is stamped outwardly from the reflecting surface, 16, thereby forming in effect a series of stepped parabolic reflecting surfaces whose focus is such that rays of light striking them from the bulb 8, will be directed downwardly upon the roadway at different points slightly in advance of the vehicle. As will be observed from Fig. 1 the steps are formed gradually wider and of less depth as they approach the upper part of the reflector. The purpose of forming these steps in this manner is for the reason that the greatest glare is directly behind the bulb, and decreases in intensity outwardly. The ends of each of the steps gradually merge into the surface 16.

As will be observed, the steps are arranged in a horizontal parallel relation, so that all rays of light directed thereon will be reflected downwardly.

The lowermost step is extended downwardly adjacent the bulb to form a flattened downwardly tipped portion 17 close to the bulb which kills the glare at this point by directing the light rays downwardly.

The usual lens and lens retaining ring 18 and 19 are provided. The reflector is also provided with the usual socket 20 for the reception of the bulb and the wire engaging plug 21.

It will be seen from the foregoing that a reflector has been provided which will effectively eliminate all glare while at the same time supplying a maximum of light. The greatest glare to an advancing driver from the ordinary parabolic reflector, when the light bulb is properly focused is from the upper half of the reflecting surface, and it was with this fact in mind, that the present reflector was designed.

It is to be understood that the form of the invention herein shown and described is to be taken as the preferred form, but that various changes in the shape, size and number of sectors, may be resorted to without departing from the spirit of the invention or the scope of the subjoined claims.

2
Having described my invention, what I claim as new and desire to secure by Letters Patent is:—

1. A parabolic lamp reflector having a plurality of straight horizontally arranged stepped portions extending entirely across the upper half thereof from side to side and arranged to direct light rays received from a source of light placed at its focus downwardly and substantially at the same angle of inclination at all points in the length of said stepped portions.
2. A lamp reflector having its upper half provided with a plurality of straight horizontally arranged stepped portions complementally forming a vertically serrated face

arranged to direct light rays received from a source of light placed at its focus downwardly, said stepped portions increasing in width from the center outwardly and each of stepped portions directing light rays downwardly at the same angle of inclination throughout its length. 20

3. A structure as recited in claim 2 wherein the connecting portions between the steps lie at such an angle as not to be impinged by light rays from the source of light. 25

In testimony whereof I hereunto affix my signature.

JAMES N. LYLES.
